UNITED STATES PATENT OFFICE

156,935

FOLDING CHAIR

Carl T. Carlson, Iron Mountain, Mich.

Application January 3, 1949, Serial No. 14

Term of patent 7 years

(Cl. D15—1)

To all whom it may concern:

Be it known that I, Carl T. Carlson, a citizen of the United States, residing at Iron Mountain, in the county of Dickinson and State of Michigan, have invented a new, original, and ornamental Design for a Folding Chair, of which the following is a specification, reference being had to the accompanying drawing, forming part thereof.

Figure 1 is a perspective view of a folding chair, showing my new design and illustrating the same in an erected position, and

I claim:

The ornamental design for a folding chair, as shown.

CARL T. CARLSON.
